WIRE DISPENSER

Ted Goddard, Los Angeles, Calif.

Application August 16, 1949, Serial No. 110,572

3 Claims. (Cl. 242—129)

1

This invention relates to a device for facilitating the dispensing of wire from a coil of wire.

The object of the invention is to provide a device for holding a coil of wire therein, and wherein the wire coil can be readily unwound as needed.

Another object of the invention is to provide a wire handling device which includes a means for readily attaching the device to a supporting member, the device being constructed so that the parts thereof can be moved to an out of the way position whereby the coil of wire can be positioned therein.

A further object of the invention is to provide a wire handling device which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a top plan view of the wire handling device, according to the present invention;

Figure 2 is a front elevational view of the wire handling device;

Figure 3 is a side elevational view of the device; and

Figure 4 is a front elevational view of the device, showing certain parts thereof swung to an out of the way position to enable positioning of a coil of wire in the frame.

Referring in detail to the drawings, there is shown a wire handling device which includes a frame 10 that is semi-cylindrical in shape, and the frame 10 may be made of any suitable material. The frame 10 includes an arcuate or semi-circular vertically disposed bottom strap 11. The frame 10 further includes a horizontally disposed back strap 12 which has each of its ends curved as at 13 and 14, and the upper end of the bottom strap 11 are secured to the curved ends 13 and 14 as by welding. Arranged below the back strap 12 and having its upper end connected thereto by a bolt and nut assembly 19, is a vertically disposed body member 18. The body member 18 is shaped to define a curved portion 20 which is secured to the bottom strap 11 as by welding. The frame 10 further includes a pair of right angularly arranged braces 28 and 29 and each brace has its lower end secured to the free or front end 26 of the body member 18, as by welding, while the upper end of the braces are connected to the ends of the strap 12, as by welding. The various parts of the frame 10 are rigidly connected

2

together so as to provide a support for the coil of wire 23, dotted lines Figure 2.

A means is provided for retaining the coil of wire 23 in the frame and this means comprises a support member 24 which is vertically disposed, and the support member 24 has its lower end pivotally connected to the back strap 12 by the bolt and nut assembly 19. The other end of the support member 24 is shaped to define a curved section 25, Figure 3, and the support member 24 terminates in a vertical section 26, there being an opening 27 in the vertical section 26 for a purpose to be later described.

An arm 30 has its lower end pivotally connected to the frame 10 by the bolt and nut assembly 16, there being an opening 31 in the other end of the arm 30, Figure 4. A second arm 32 has its lower end pivotally connected to the frame 10 by means of the bolt and nut assembly 17, and the arm 32 is provided with an opening 33 therein. The arms 30 and 32 coact with the support member 24 to prevent accidental movement of the coil 23 out of the frame 10.

A bolt 34 is adapted to be inserted or projected through the openings 27, 31 and 33 when the coil 23 has been positioned in the frame 10. Then, a wing nut 35 is arranged in threaded engagement with the bolt 34 for maintaining the parts in assembled relation.

Secured to the exterior or rear surface of the support member 24 is a strap 36, and a ring 37 is connected to the upper end of the strap 36. The ring 37 is adapted to be arranged in engagement with a nail, hook, or other securing element whereby the entire wire handling device can be supported from a vehicle or other supporting structure.

In use, to position a coil of wire 23 in the device, the wing nut 35 is removed from the bolt 34, and after the bolt 34 has been removed out of the openings 27, 31 and 33, the arms 30 and 32 and the support member 24 are swung or pivoted to the position shown in Figure 4. Then, the coil or wire 23 is positioned in the frame 10 and the arms 30, 32 and the support member 24 are returned to the position shown in Figures 1, 2 and 3. Then, the bolt 34 is again inserted through the openings 27, 31 and 33, and the wing nut 35 is arranged in engagement with the bolt 34 to maintain the parts in assembled relation. The coils of wire can be readily dispensed from or through the opening in the front of the device.

From the foregoing, it is apparent that a wire dispenser has been provided wherein coiled wire of various sizes and in any length can be dis-

pensed therefrom. By using the device of the present invention, the wire is kept intact in the original roll and only that portion of the wire which is being dispensed is unwound so that the wire does not become tangled and difficult to handle. Further, the dispensing device can be hung from any convenient supporting member by means of the ring 37.

What I claim is:

1. In a wire handling device, a semi-circular frame for holding a coil of wire therein, said frame comprising a vertically disposed semi-circular bottom strap, a horizontally disposed back strap having its ends curved and secured to the upper ends of said bottom strap, a vertically disposed body member having its upper end connected to said back strap intermediate the ends thereof, said body member terminating in a curved portion, a pair of vertically disposed diverging braces each having an end secured to said curved portion and the other end secured to the curved ends of said back strap, a support member having its lower end pivotally connected to the back strap of said frame and its other end shaped to define a curved section, and a pair of arms each having one end pivotally connected to the curved ends of said back strap, and means for connecting the other ends of said arms to the curved section of said support member.

2. In a wire handling device, a semi-circular frame for holding a coil of wire therein, said frame comprising a vertically disposed semi-circular bottom strap, a horizontally disposed back strap having its ends curved and secured to the upper ends of said bottom strap, a vertically disposed body member having its upper end connected to said back strap intermediate the ends thereof, said body member terminating in a curved portion, a pair of vertically disposed diverging braces each having an end secured to

35 said curved portion and the other end secured to the curved ends of said back strap, a support member having its lower end pivotally connected to the back strap of said frame and its other end shaped to define a curved section, and a pair of arms each having one end pivotally connected to the curved ends of said back strap, and means for connecting the other ends of said arms to the curved section of said support member, a strap 10 secured to the rear surface of said support member, and a ring connected to the upper end of said last named strap for supporting said wire handling device from a supporting structure.

15 3. In a wire-handling device, a semi-circular frame for holding a coil of wire therein, said frame comprising a bottom strap, a back strap having its ends curved and secured to the upper end of said bottom strap, a body member having its upper end connected to said back strap intermediate the ends thereof, said body member terminating in a curved portion, a pair of diverging braces each having an end secured to said curved portion and the other end secured to the curved end of said back strap, a support member 20 having its lower end pivotally connected to the back strap of said frame and its other end shaped to define a curved section, and a pair of arms each having one end pivotally connected to the curved end of said back strap and means for connecting the other ends of said arms to the curved sections of said support member.

TED GODDARD.
